UNITED STATES PATENT OFFICE.

JAMES JETT RANDOLPH, OF TULSA, OKLAHOMA.

PUMP JACK.

Application filed August 20, 1926. Serial No. 130,532.

This invention relates to an improved pump jack, the general object of the invention being to give the pump rod a straight reciprocatory movement by eliminating the side motion so as to prevent undue wear on the packing gland at the mouth of the casing.

This invention also consists in certain other features of construction and in the combination and arrangement of the several parts, to be hereinafter fully described, illustrated in the accompanying drawings and specifically pointed out in the appended claims.

15 In describing my invention in detail, reference will be had to the accompanying drawings wherein like characters denote like or corresponding parts throughout the several views, and in which:—

20 Figure 1 is an elevation showing the invention in use.

Figure 2 is a plan view.

Figure 3 is a section on line 3—3 of Figure 2.

25 Figure 4 is a section on line 4—4 of Figure 2.

In these views, 1 indicates a base upon which the vertical supporting frame 2 of the rocking lever 3 is pivoted, this lever being connected at its free end to the pump rod 4 which enters the pump casing 5 through the gland 6. A bell crank 7 is connected with the tubular shaft 8 which is rotatably mounted on the stationary shaft 9 which is carried by the posts 10 on the base. The power rod 11 is connected with one arm of the bell crank and a link 12 connects the other end with the lever 3 so that the rocking movement of the bell crank, imparted to it by the rod 11, will be transmitted to the lever 3 to oscillate the said lever, which in turn reciprocates the rod 4. As is well known, this movement will give a side pull to the rod 4 so that an undue wear is placed on the gland 6. In order to overcome this, I provide means for moving the lever 3 and its supporting frame 2 forwardly to prevent sidewise movement of the rod 4. This movement is imparted to the frame 2 through means of the arms 13 on the ends of the tubular shaft 8 and which are connected with

the forwardly extending brackets 14 on the frame 2 by the links 15.

Thus as the bell crank is rocked by the rod 11, its rocking movement will be communicated to the frame 2 through means of the arms 13 and links 14 so that the said frame 2 is rocked on its pivot and thus the member 3 will be moved bodily and thus its end which is pivoted to the rod 4 will remain at all times over the vertical center of the casing 5 and thus the rod 4 will be moved in a vertical plane without any side motion. The drawings show the frame 2 and lever 3 as formed of frame-like structures but it will, of course, be understood that these parts may be formed of single bars.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A jack of the class described comprising a lever adapted to be connected with the pump rod, a pivoted support to which the lever is pivotally connected, a bell crank connected with the lever for oscillating the same, means for connecting the bell crank with a source of power and means for connecting the bell crank with the support for rocking the support by the movement of the bell crank.

2. A jack comprising a base, a vertically arranged frame pivoted at its lower end to the base, an oscillatory lever pivoted at one end to the upper end of the frame, a pump rod connected with the other end of the lever, a bell crank pivotally supported on the base, a link connecting one end of the bell crank to the lever, a rod connecting the other end of the bell crank to a source of power, an arm connected with the bell crank at the junction of its two arms, a link connected with the arm and a forwardly extending part on the frame to which the link is connected.

In testimony whereof I affix my signature.

JAMES JETT RANDOLPH.
